UNITED STATES PATENT OFFICE.

CLINTON KEISER, OF ZANESVILLE, OHIO.

DESIGN FOR A ROOF-TILE.

SPECIFICATION forming part of Design No. 26,717, dated March 2, 1897.

Application filed April 22, 1896. Serial No. 588,642. Term of patent 7 years.

To all whom it may concern:

Be it known that I, CLINTON KEISER, a citizen of the United States, residing at Zanesville, in the county of Muskingum and State 5 of Ohio, have invented and produced a new and original Design for Roof-Tiles, of which the following is a specification, reference being had to the accompanying drawings, forming part thereof.

- 10 Figure 1 is a face view of my tile design. Fig. 2 is a similar view of a modification thereof. Fig. 3 is a sectional view on line $\alpha\alpha$ of Fig. 1, and Fig. 4 is a sectional view on line yy of Fig. 2.
- 15 Similar letters refer to similar parts throughout the several views.

The leading feature of my design is a roof-tile plate having raised or parallel flutes or rolls which extend longitudinally thereon 20 and arranging said flutes or rolls within border projections.

a represents the body of the tile-plate, which is oblong in form, and b represents parallel flutes or rolls which are arranged 25 longitudinally thereon and which are raised

from said body. The upper end of the tile-plate is provided with a transverse shoulder portion, (indicated at c .) from the outer side of which rises a raised lip d . One of the longer sides of my newly-designed tile-plate 30 is bordered by a roll or flute e , which is parallel with the rolls b , but which presents, as shown, a much larger surface, being wider in cross-section than the small rolls b and of greater height. The remaining longer side 35 of the tile-plate is bordered with parallel longitudinally-arranged lips f and g , which project above the surface of the rolls b . By thus providing a raised upper end portion and raised side portions it will be seen that 40 a central panel is provided with a depressed fluted surface.

What I claim is—

The design for a roofing-tile substantially as herein shown and described.

CLINTON KEISER.
